US0D1020524S

(12) **United States Design Patent** (10) **Patent No.:** **US D1,020,524 S**
(45) **Date of Patent:** **** Apr. 2, 2024**

(54) **DEVICE FOR ROTATING ORNAMENTS**

- (71) Applicants: **Gale Scott Houdashell**, Amarillo, TX (US); **Charles Curtis McGill**, Amarillo, TX (US)
- (72) Inventors: **Gale Scott Houdashell**, Amarillo, TX (US); **Charles Curtis McGill**, Amarillo, TX (US)
- (73) Assignee: **Hey BUDDY Hey Pal Investments LLC**, Amarillo, TX (US)

(**) Term: **15 Years**

(21) Appl. No.: **29/732,941**

(22) Filed: **Apr. 28, 2020**

Related U.S. Application Data

- (63) Continuation-in-part of application No. 16/742,752, filed on Jan. 14, 2020, now abandoned, which is a continuation of application No. 15/900,402, filed on Feb. 20, 2018, now Pat. No. 10,531,749.

CLAIM

The ornamental design for a device for rotating ornaments, as shown and described.

DESCRIPTION

FIG. 1 is a front view of a device for rotating ornaments, showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a perspective view thereof.

The broken lines shown in the drawings represent portions of the device for rotating ornaments that form no part of the claimed design.
